UNITED STATES PATENT OFFICE.

WILLIAM DANIEL SAUER, OF ASHTON, IOWA.

FOUR-HORSE EVENER.

SPECIFICATION forming part of Letters Patent No. 380,522, dated April 3, 1888.

Application filed November 21, 1887. Serial No. 255,765. (No model.)

To all whom it may concern:

Be it known that I, WILLIAM DANIEL SAUER, a citizen of the United States, and a resident of Ashton, in the county of Osceola and State 5 of Iowa, have invented certain new and useful Improvements in Four-Horse Eveners; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a perspective view of my new 15 and improved four-horse evener. Fig. 2 is a front elevation of the same. Fig. 3 is a detail view of the braced arm and that part of the tongue to which it is secured, and Fig. 4 is a detail view of that end of the cross-bar to 20 which the stirrup is secured.

The same numerals of reference indicate corresponding parts in all the figures.

My invention consists in a new and improved 25 four-horse evener which is designed for use on self-binding reapers, and my invention will be hereinafter fully described and claimed.

Referring to the several parts by their designating numerals, 1 indicates the tongue of a self-binding reaper to which my four-horse 30 evener is shown secured in its operative position.

2 indicates a stationary arm, which is secured at its inner end upon the tongue at a proper distance from the rear end of the same, extending 35 out to the right-hand side, and being firmly braced by the lower inclined brace, 3, and the rear inclined brace-rod, 4, as shown. Upon the outer end of this stationary arm is pivotally secured the cross-bar 5, which is centrally pivoted 40 by the vertical pivot-bolt 6, which passes down through the center of the cross-bar and through the outer end portion of the stationary arm, a washer, 7, being placed upon the pivot-bolt between the cross-bar and the arm to raise 45 the bar and thus greatly reduce friction.

Upon the left-hand end of the cross-bar is bolted a stirrup, 8, between the front ends, 9 50, of which is centrally pivoted a doubletree, 10, having pivotally secured to its ends by the links 11 11 the singletrees 12 12^a. To the rear projecting part of this stirrup is secured one end of a rope or cable, 13, which then extends

back and around a grooved pulley, 14, which is journaled in a bracket, 15, on the rear end of the tongue. The rope, after passing back 55 around this rear grooved pulley, 14, runs forward to the other end of the cross-bar 5. This other end or right-hand end of the cross-bar is formed with the longitudinal horizontal slot 60 16, in the inner end portion of which is journaled on a vertical pivot a grooved pulley, 17. The right-hand end portion of the cable or rope passes forward through this slot, so as to run in the grooved pulley 17, and has secured to its forward end a clip or stirrup, 18, the 65 eyed ends of which are bolted to the center of a doubletree, 19, to the ends of which are pivotally secured by the links 20 20 the singletrees 21 21.

Now it will be seen that the several parts 70 are so arranged that when the four horses are attached to the singletrees three of the horses will be on the right-hand side of the tongue, the horse attached to the singletree 12^a at the left-hand end of the cross-bar being on the 75 right-hand side of the tongue.

It will be seen that by the use of my new and improved evener four horses can be driven abreast at the tongue of a self-binding reaper, and that three of the four will be on the right-hand side of the tongue, which is absolutely necessary in using four horses abreast to a 80 reaper.

It will be seen that by securing one pair of horses to the end of the cross bar and running 85 the rope from that end of the bar around the rear pulley, through a slot in the other end of the bar, and securing the other team or pair of horses directly to that end of the rope, the horses will all work or pull from the rear 90 pulley near the binder, and as the cross-bar is centrally pivoted the strain will always be equally distributed between the horses, no matter if one team gets ahead of the other. They will always have to pull the same, and 95 there will be no side draft.

From the foregoing description, taken in connection with the accompanying drawings, the construction, operation, and advantages of my invention will be readily understood. It will 100 be seen that my new and improved evener for four horses is simple and strong in construction, and can be manufactured at a comparatively small cost, while it is exceedingly effect-

ive in its operation. By its use four horses can be worked abreast to the tongue of a self-binding reaper, and three of the four will be on the one—the right-hand—side of the tongue, 5 and the draft will be equally distributed at all times.

Having thus described my invention, what I claim, and desire to secure by Letters Patent of the United States, is—

1c 1. The combination, with the tongue of a reaper, of the stationary arm, the cross-bar centrally pivoted to the outer end of the said arm and having a grooved pulley journaled in a slot in its right-hand end, a doubletree attached to the left-hand end of the cross-bar and having the singletrees, the grooved pulley secured upon the rear of the tongue, and a rope secured at one end to the left-hand end of the cross-bar, passing around the rear grooved pulley upon the tongue, through the slotted right-hand end of the said bar, and having attached to its right-hand end a doubletree provided with two singletrees.

2. The combination, with the tongue of a 25 reaper, of a stationary arm, the centrally-piv-

oted cross-bar having a stirrup secured to its left-hand end and having a grooved pulley journaled in a slot in its right-hand end, the grooved pulley pivoted upon the rear of the tongue, the rope arranged as described, and 30 the right-hand double and single trees.

3. The combination, with the tongue of a reaper, of the stationary arm and the braces for the same, the centrally-pivoted cross-bar having the stirrup secured to its left-hand end 35 and having a grooved pulley journaled in a slot in its right-hand end, the grooved pulley journaled upon the rear end of the tongue, the rope arranged as described, and the doubletrees having the singletrees secured by the 40 links to their ends, substantially as and for the purpose set forth.

In testimony that I claim the foregoing as my own I have hereunto affixed my signature in presence of two witnesses.

WILLIAM DANIEL SAUER.
